UNITED STATES PATENT OFFICE.

JOHN W. HOWELL, OF NEWARK, NEW JERSEY, ASSIGNOR TO THE GENERAL ELECTRIC COMPANY, OF NEW YORK.

PRODUCING HIGH VACUUMS.

SPECIFICATION forming part of Letters Patent No. 660,816, dated October 30, 1900.

Application filed August 31, 1899. Serial No. 729,076. (No specimens.)

To all whom it may concern:

Be it known that I, JOHN W. HOWELL, a citizen of the United States, residing at Newark, county of Essex, State of New Jersey, have 5 invented certain new and useful Improvements in Producing High Vacuums, (Case No. 1,376,) of which the following is a specification.

My invention relates to the production of 10 high vacuums, and is particularly adapted for service in connection with the exhaustion of incandescent electric lamps. By the methods commonly employed in the manufacture of incandescent lamps, gases, including air and 15 hydrocarbon gases, are trapped or occluded in the filament and its joints and moisture is deposited on the walls of the bulb, the last traces of which are exceedingly difficult to remove and in the case of high-voltage lamps 20 require for satisfactory life of the filament a long-continued exhaustion by the pump. A good vacuum may be established by mechanical pumps, the design of which is familiar to those skilled in the art, but at the 25 expense of considerable time for exhaustion. Methods have been designed for promoting rapidity of exhaustion and the removal of the last traces of deleterious gases, so as to produce a satisfactory vacuum, by introducing 30 within the bulb neutral or inert gases and then again continuing the exhaustion; but difficulty is experienced in providing an inert gas which is sufficiently free from impurities to afford a satisfactory result. Other methods 35 have been proposed for acting chemically upon the residual gases occluded in the filament and its joints by vaporizing solids or liquids capable of combining with them and removing the products of the reaction.

40 My process affords a means for establishing a high vacuum at a lower cost than by any method heretofore proposed with which I am familiar.

I carry out my invention by producing a 45 preliminary exhaustion by the aid of a pump, for which I prefer to employ a good type of mechanical pump, then subjecting the lamp to external heat to drive off any moisture deposited on the internal walls of the bulb, 50 and then continuing the exhaustion with the filament brought to incandescence. I then

admit to the bulb a determinate volume of phosphin or phosphoreted hydrogen gas at ordinary atmospheric temperatures, which acts not only mechanically as a vehicle for 55 assisting the exhaustion of the residual gases by a washing-out action, but establishes a chemical reaction with such hydrocarbon vapors or air as may be present, and thus effects their extraction from the bulb upon further action of the pump and exhaustion of the phosphoreted hydrogen. The result on a lamp treated according to my process is a very high vacuum and an increased output 60 of fifty per cent. in the product of an operator's work during a given period and a resultant cheapening of the cost of the lamp. This decrease in the expense is an incident principally of the gaseous treatment by which a gang or group of lamps may be simultaneously subjected to the action of the gas, and 65 an attendant may therefore manage several independent machines or exhausting devices. 70

No particular organization of apparatus is required to carry out my invention, except 75 provisions for pumping off the air or gases and for introducing the phosphin. It will, however, greatly facilitate an increased output per operator to follow the usual plan of connecting with each pump an exhaustion- 80 tube having a plurality of air-tight sockets or openings to receive the stems of a group of lamps. The arrangement of such apparatus and the construction of the lamp are so familiar to those skilled in lamp manufacture 85 that I deem it unnecessary to show the apparatus in detail.

The accompanying drawing shows a well-known form of lamp-bulb in which a tubular stem 1 is left after the pillar carrying the filament has been sealed into the neck of the lamp and by which the exhausting processes are conducted, after which the bulb 2 is sealed off near its junction with the stem and the lamp is ready for the market. 90

In practicing my process the stem 1 is connected by an elastic joint in the usual manner with a pump, for which I prefer to employ a mechanical pump, and a group of eight or more lamps are similarly connected to the same pump. A rough exhaustion is then made and the usual tests for defects in the 95

lamp structure or filament-joints made by connecting with an induction-coil or other source of high-tension current. The filament is then raised to a high temperature by passing a current through it and allowed to burn a short time to allow the pump to exhaust the occluded gases. A definite graduated quantity of phosphoreted hydrogen is then admitted to the group of lamps by means of 5 a controllable admission-cock connected with the exhaustion-pipe while the lamps are burning, and after a short interval (about two minutes) the exhaustion is completed and the phosphoreted hydrogen and the products of 10 its reaction upon the residual gases will have been withdrawn. The phosphoreted hydrogen acts as a menstruum or vehicle to carry off the residual gases by diffusing throughout the bulb and mixing with them and also 15 reacts chemically upon such occluded gases as are capable of reacting with it.

I prefer to generate the phosphoreted hydrogen by heating phosphorus in a solution of caustic potash, though other methods, such 20 as heating it with milk of lime or mixing phosphid of calcium with water, may be employed. In any of these processes the phosphoreted hydrogen (PH_3) is not chemically pure, but carries with it more or less vapor 25 of the liquid phosphid of hydrogen, (P_2H_4), which has a great affinity for certain gases, and especially oxygen at reduced pressures. I believe the hydrocarbons present are 30 decomposed by the action of the phosphoreted 35 hydrogen, which takes on an additional atom or atoms of hydrogen at the expense of the hydrocarbon gases in the bulb, and thereby facilitates an almost complete exhaustion of the residual gases. The heating of the lamp 40 both internally and externally during the operation drives off any film of moisture which

may be deposited upon the inner wall of the globe or other parts, which is removed with the gas by the pump.

What I claim as new, and desire to secure 45 by Letters Patent of the United States, is—

1. The process of producing high vacuums, consisting in exhausting air or other gas from the inclosure, then admitting phosphoreted hydrogen and again exhausting the inclosure. 50

2. The process of producing a high vacuum in an incandescent lamp, consisting in first exhausting the air and other gases from the bulb, then admitting phosphoreted hydrogen, then again exhausting the bulb. 55

3. The process of producing a high vacuum in an incandescent lamp, consisting in exhausting the air and other gases from the bulb in which the filament is mounted, then admitting a compound gaseous at ordinary 60 atmospheric temperatures having an affinity for the residual gases in the bulb, then exhausting the bulb.

4. The process of producing a high vacuum in an incandescent lamp, consisting in exhausting the air and other gases from the bulb, heating the lamp, admitting a determinate quantity of phosphoreted hydrogen, then exhausting and sealing off the lamp. 65

5. The process of producing a high vacuum 70 in an incandescent lamp, consisting in first exhausting the bulb, then heating the filament and walls of the lamp, then admitting phosphoreted hydrogen to the bulb, then again exhausting.

In witness whereof I have hereunto set my hand this 23d day of August, 1899.

JOHN W. HOWELL.
